HANDKERCHIEF RETAINER
Henri Weber, 57-18 162nd St., Flushing, N.Y.
Filed June 27, 1961, Ser. No. 119,870
1 Claim. (Cl. 24-3)

This invention relates to an improved handkerchief retainer, and more particularly a retainer which may be advantageously utilized to position and maintain the position of a handkerchief placed in a breast pocket of a jacket.

It is a prime object of the invention to provide a new and useful article of manufacture which is economical to manufacture, positive in action for the purpose intended, and meets a long time need of the well dressed man.

Other objects and advantages of the invention will be obvious to those skilled in the art from a reading of the specification and claim when taken with the drawing, wherein:

FIGURE 1 is a view of the handkerchief retainer including a handkerchief therein.

FIGURE 2 is a sectional view taken along line 2-2 of FIGURE 1.

FIGURE 3 is an open view of the article of FIGURE 1, less the handkerchief.

FIGURE 4 is a view of the handkerchief retainer in the breast pocket of a garment.

Referring to the drawing and more particularly to FIGURE 3, the invention comprises a pair of side walls 10 and 12 hingedly connected by a pin hinge 14 at their respective edges 10a and 12a. Edges 10b and 12b remote the hinged edges are provided with coacting latch means 10c and 12c, which cooperate to retain the side walls in relative fixed position when the handkerchief retainer is closed.

A feature of the invention resides in the use of dimples on the interior wall which cooperate with suitable depressions in the interior wall of the device. Such dimples are shown at 16 and the depressions at 18.

To provide a space wherein the handkerchief may be placed, a lip is formed on three sides of both sidewalls 10 and 12, the lip being designated by the reference numerals 10d and 12d. The open extremity being provided for the protrusion of the handkerchief.

2

In operation, the two sidewalls are separated by the opening of the coacting latch 10c and 12c, and a handkerchief A is positioned as desired to protrude above the open edge of the retainer. The two side walls are then again latched in closed position and the device placed in the breast pocket of the wearer.

It is obvious that the invention lends itself to manufacture in either one of the known suitable plastics or metals. It is further obvious that one skilled in the art could vary the formation of the retaining means for the handkerchief from that of dimples to that of ridges or squares or the like without departing from the spirit and scope of my invention, and I therefore desire that the appended claims be given as broad an interpretation as is consistent with laws governing the grant.

What is claimed is:

A handkerchief retainer pocket comprising a pair of hingedly connected side walls, a lip around three edges of each of said side walls, latch means for locking said sidewalls in parallel spaced relation to each other to form a container open at one end thereof, and means for frictionally retaining a handkerchief against movement relative to said sidewalls, said means comprising dimples on one interior wall and cooperating confronting depressions on said other side wall, said latch means and hinge connection being located externally of the lips to prevent snagging of a retained handkerchief thereby, and said dimples and depressions having a depth substantially equal to that of the lips.
